UNITED STATES PATENT OFFICE.

ERNST LAUSCHKE, OF CHICAGO, ILLINOIS, ASSIGNOR TO BARNHART BROS.
& SPINDLER, OF SAME PLACE.

DESIGN FOR A FONT OF PRINTING-TYPE.

SPECIFICATION forming part of **Design No. 18,394, dated June 19, 1888.**

Application filed April 29, 1888. Serial No. 272,312. Term of patent 14 years.

To all whom it may concern:

Be it known that I, ERNST LAUSCHKE, a subject of the Emperor of Germany, residing at Chicago, Illinois, in the county of Cook, have 5 invented a certain new and original Design for a Font of Printing-Type, which is set forth in the following specification, reference being had to the accompanying typographical impressions, which are exact representations of said 10 design.

This design is for a font of printing-type comprising capitals, characters, and points, and is a heavy solid-faced type without ornaments. Its peculiarities are as follows: The 15 main stems terminate squarely at their upper ends, and are provided with ceriphs at their lower ends. It has letters—as B, D, O, P, Q, and R—whose stems are broken near the tops at an oblique angle. It also has letters—as C, 20 E, F, G, L, S, T, and Z—whose horizontal

strokes are provided with ceriphs which are sharply-pointed abrupt tapers. It also has letters—as N, U, V, W, and Y—which have at the upper ends of one or more of their stems a heavy inwardly-extending horizontal stroke. 25 Minor peculiarities are the long cross-strokes of the E and F and the termination of the stems of the V and W.

I claim—

The design for a font of printing-type herein 30 shown and described, comprising capitals, characters, and points, having letters whose stems are thickened at their lower ends, and whose horizontal strokes are provided with ceriphs, which are sharply-pointed abrupt 35 tapers, substantially as described.

ERNST LAUSCHKE.
